UNITED STATES PATENT OFFICE

HOMER P. CHANDLER, OF MANSFIELD, OHIO, ASSIGNOR TO THE OHIO BRASS COMPANY,
OF MANSFIELD, OHIO, A CORPORATION OF NEW JERSEY

MOLDED RECEPTACLE

Original application filed April 3, 1925, Serial No. 20,403, now Patent No. 1,720,263, dated July 9, 1929.
Divided and this application filed March 10, 1928. Serial No. 260,703.

My invention relates to a conductor or casing for an electric circuit controlling device and particularly to that class of controlling devices which is arranged to break an electric circuit under heavy current load and operated either manually or automatically and which device is likely to be used in damp places or where the air is laden with moisture as in the case of mines. The object of my invention is to provide a casing for such circuit controlling devices and used under the conditions stated which will thoroughly insulate the device from ground and will prevent the entrance of moisture to the interior of the casing, and which will at the same time permit the gases formed in the casing, when the circuit is broken therein, to escape and prevent the formation of pressure within the casing.

My invention resides in the new and novel construction, combination and relation of the various parts hereinafter fully described and shown in the drawings accompanying this specification in which:

Fig. 1 is a back face view of my invention, partial section and with the covers removed.

Fig. 2 is a front face view of my invention with the covers removed.

Fig. 3 is a sectional view of my invention on the line 3—3 of Fig. 1 but with the covers shown in place.

Fig. 4 is a face view of the back cover for use in my invention.

This application is a division of my co-pending case Serial No. 20,403 filed April 3, 1925, now Patent No. 1,720,263, issued July 9, 1929.

I have shown in the above figures a receptacle suitable for use in mines for containing a circuit breaker. Under such use the air is usually charged heavily with moisture which is very likely to condense and, therefore, I provide a receptacle formed of insulating material in which the switching apparatus may be substantially enclosed and

which is provided with venting means such that the gases formed within the receptacle upon the opening of the automatic switch may escape. At the same time, the venting is of such construction that the arc formed within the receptacle will be confined to the receptacle and thereby avoid danger of igniting gases which may surround the receptacle and with which mine air is more or less heavily charged.

In the preferred embodiment of my invention I employ a casing 1, preferably of insulating material and formed to any shape desired to meet the requirements. The casing may be formed of a mixture of fibers and gums such as asbestos and shellac together with any other modifying ingredients if desired and which material may be formed into any shape desired by softening the material under heat, placing it in properly shaped and constructed dies and then subjecting it to heavy pressure to force it to fill the cavity in the die, thereby assuming the desired shape, and after the material has been cooled, remove the molded piece from the die.

Formed within the casing is a transverse insulated diaphragm 2 and provided with an opening 3 therein to receive the switch operating shaft. Mounted within the casing 1 and projecting therefrom is an arc chute 5 which has a cap 6 mounted thereon and secured to the chute 5 by means of the screws 7.

Between the chute 5 and the cap 6 is an air space 8 communicating with the interior of the chute 5 so that any gases formed within the casing 1 will be allowed to escape from within the casing. It will be understood, of course, that the opposite faces of the casing which are shown in Figs. 1 and 2 are provided with covers 9 and 10 and these covers are secured to the casing 1 by means of fastening devices 11 extending through the casings and the covers, and by means of the projecting lugs secured to one end of the through-bolt 11. Arcs 11 and 11a are held

in place by the nuts 12. The lugs 11a are provided with holes 4 which may be used in mounting the device in position, as, for instance, on a side wall. The members 11a may be merely short projecting lugs or may consist of a single bar extending entirely across the back of the box and projecting from each side.

The interior of the casing 1 is formed with two recesses 14 and 15 and separated by the diaphragm 2 and in the interior corners of the casing are formed fillets 16 with a transverse hole 13 in each. The through-bolt 11 is positioned in the hole 13.

The arc chute 5 is provided with two flat spaced walls 5a and 5" and also with the two angularly disposed walls 5'. The arc chute 5 is formed of insulating material, but preferably of a material which is not readily affected by the arc, as for instance, a material formed of asbestos and portland cement. This chute may also be formed in dies from a plastic material. The wall 5" is short as compared with the wall 5a and its lower edge rests upon the upper outer wall 17 and is readily placed in position when the cover 9 is removed and is prevented from being moved outwardly through the fact that its walls 5' interlock with the upper sloping walls 18 of the casing, and the chute 5 cannot be removed sideways on account of the interlocking of the said walls, nor can it be moved laterally when the cover 9 has been positioned.

Mounted upon the chute in an inverted cup shaped member 6 which is held in position by means of the screws 7 which pass through lugs 19 on the cap and into lugs 20 on the chute. The chute 5 is provided with the upper opening 21 and the lugs 19, spacing the cap from the chute to form a recess 22 which communicates with the passage 8 to the external air. The cover 6 is formed of insulated material and preferably the same as the chute 5.

The back cover 9 and the front cover 10 may be of the same shape and size if desired or any suitable size and shape to meet requirements, and are each provided with holes 23 which correspond with the holes 13 in the casing. The front cover 10 is provided with the opening 24 through which passes the operating handle for the switch within the casing. The side walls of the casing may be provided with the openings 25 and through which may extend the cables connected to the mechanism within the casing.

In the particular construction of the case shown in the drawings, the wall 5a has been spaced from the wall 2 a sufficient distance to make the portion of the switch which opens the circuit and this would leave a space between the wall 5a and the cover 9, therefore I insert a panel 69 which fills the space between the walls 5a and 9. If the part of the switch for opening the circuit is of great-

er width than the space between the wall 2 and the wall 5a, it can be increased up to a point where the wall 5a would contact with the cover 9, in which case there would be no insert panel 69.

It will, of course, be evident that the shape of the case, the dimensions and openings may differ from those shown in the drawings to suit various apparatus.

I find that there is less likelihood of condensation of moisture from the air with the casing composed of insulating material as herein described. The surface leakage is also very small.

Having disclosed my invention I wish to be limited only by my claims.

I claim:

1. A switch receptacle comprising a casing member of formed up material having integral side and bottom walls and an integrally formed partition transversely disposed relative to the walls forming two compartments each open on opposite faces of the receptacle, a separately formed and removable cover for each compartment and positioned parallel with the fixed partition, transversely disposed registering openings in the cover of one compartment and the partition, a top side for the said one compartment formed integral with the sides and transversely disposed partition, a separately formed chute projecting from the top opening in the other compartment and a separately formed cover for said chute to enclose the top and sides of said chute with an air space therebetween and means to secure the covers in place.

2. A switch receptacle comprising a casing member of formed up material having integral side and bottom walls and an integrally formed partition transversely disposed relative to the walls forming two compartments each open on opposite faces of the receptacle, a separately formed and removable cover for each compartment and positioned parallel with the fixed partition, transversely disposed registering openings in the cover of one compartment and the partition, a top side for the said one compartment formed integral with the sides and transversely disposed partitions, a separately formed chute projecting from the top opening in the other compartment and beyond said top side and a separately formed cover for said chute to enclose the top and sides of said chute with an air space therebetween and means to secure the covers in place.

3. A switch receptacle comprising a casing member of formed up material having integral side and bottom walls and an integrally formed partition transversely disposed relative to the walls forming two compartments each open on opposite faces of the receptacle, a separately formed and removable cover for each compartment and positioned parallel with the fixed partition, transverse-

ly disposed registering openings in the cover of one compartment and the partition, a top side for the said one compartment, a separately formed chute projecting from the top opening in the other compartment and a separately formed cover for said chute to enclose the top and sides of said chute with an air space therebetween and transversely disposed means to secure the covers in place.

5 10 In testimony whereof I affix my signature.
